Primary Examiner—M. N. Pandozzi

(74) *Attorney, Agent, or Firm*—Greenblum & Bernstein,
P.L.C.

(57) **CLAIM**

I claim the ornamental design for a cup, as shown and described.

DESCRIPTION

FIG. 1 is a front perspective view of another aspect of the cup;

FIG. 2 is a front side view of the design embodiment shown in FIG. 1;

FIG. 3 is a back side view of the design embodiment shown in FIG. 1;

FIG. 4 is a left side view of the design embodiment shown in FIG. 1;

FIG. 5 is a right side view of the design embodiment shown in FIG. 1;

FIG. 6 is a top view of the design embodiment shown in FIG. 1; and,

FIG. 7 is a bottom view of the design embodiment shown in FIG. 1.

The broken lines are included for the purpose of illustration and form no part of the claimed design.

1 Claim, 7 Drawing Sheets
